UNITED STATES PATENT OFFICE.

WILLIAM ERASTUS WILLIAMS, OF CHICAGO, ILLINOIS.

STEEL END FOR FREIGHT-CARS.

1,240,110.

Specification of Letters Patent. Patented Sept. 11, 1917.

Application filed December 26, 1914. Serial No. 878,991.

To all whom it may concern:

Be it known that I, WILLIAM ERASTUS WILLIAMS, a citizen of the United States, residing at Chicago, in the county of Cook and State of Illinois, have invented a new and useful Improvement in Steel Ends for Freight-Cars, of which the following is a specification.

The object of my invention is to provide a cheaply constructed steel end that will be very rigid in every direction and yet furnish approximately a smooth surface for the inside of the car. It has for a further object of furnishing a steel end stiffened by corrugations of such a nature that when a wooden inside sheathing is used the corrugations will not be blocked off entirely leaving voids that will retain dust, but the corrugations will ventilate themselves and allow the dust to fall to the bottom and drain out through the dust space ordinarily provided for that purpose with the wooden ends. The steel sheet may be of one piece or more than one piece, that is, an integral or a compound sheet, as may be most convenient.

Reference will be had to the accompanying drawings in which Figure 1 is an end elevation of my end, the sills and draft gear not being shown.

Fig. 2 is an end elevation of a strip through the middle of the end showing a portion of a car end wherein two plates similar to the plate of Fig. 1 are overlapped.

Fig. 3 is a cross sectional elevation of the end where it joins the end plate.

Fig. 4 is a view similar to 3, but having the top edge of the end sheet turned over at the top of the end plate.

Fig. 5 is a plan section at one of the corners of the car.

Fig. 6 is a similar view but showing the corrugations carried around the corner.

In the drawing 1 indicates the sheet of metal forming the end of the car. This sheet may be one piece as is indicated by Fig. 1, or it may be composed of two or more sheets spliced as is indicated by 2 in Fig. 2.

The sheet is embossed with corrugations 3 running in a direction across the car and with corrugations 4 running vertically. At the intersections of these corrugations there are embossed cups 5 which are approximately twice as deep as the corrugations

and along any line passing through one of the cups the plate is as stiff as along any line passing at one side of the cup.

Thus my end sheet is stiffened in each direction by corrugations that are not weakened by the intersection of the other corrugations since the cups stiffen the intersections in every direction giving the plate approximately uniform stiffness although its corrugations intersect.

In the ends heretofore used for freight cars, stiffness has been provided usually in only one direction, thus either transmitting all the load across the end to the corner posts or else carrying it from the end sill vertically up to the end plate. In the first instance the corner posts are required to be stiffened by diagonal braces or ties of some kind and in the other case, the end plates on the roof structure are required to absorb the severe shocks.

In some cases a circular corrugated end is used and with it, the corner areas are not suitably stiffened by the circular corrugations, and circular corrugations do not lend themselves easily to line with wooden sheathing.

With my style of stiffened end I get a flat surface for a large part of the area on the inside of the end which is a desideratum.

When an inside wooden lining is required with my end, I insert half round wooden inserts 6 into as many of the corrugations as desired and fasten them by bolts or rivets 7 and to these inserts 6 I nail the wooden sheathing 8.

The arrangement of this sheathing may be horizontal or vertical as suits the wishes of the purchaser of the cars and in either case the inserts will obviously be located, as shown in the drawings, transversely with respect to the sheathing boards which for illustration are shown as horizontal. In other words, the inserted strips will be vertical or horizontal according as the sheathing boards are horizontal or vertical.

For a large part of the area, the wooden sheathing 8 lies against the flat surfaces of the end and thus it is sustained by the steel sheet throughout most of its area against puncture or rupture by contacts of concentrated loads like bars of iron, ends of pieces of pipe, timbers and other things; whereas with most other corrugated ends the wooden sheathing when used is supported only at

the summits of the corrugations and the larger area of the wood is exposed to rupture.

The vertical corrugations are so close together that but small sections of the horizontal corrugations are found between the cups, so that any dust that may gather in a horizontal corrugation will be likely to be jarred by the travel of the car over to the adjacent vertical corrugation and be dropped down through it to the dust gap at the floor line.

The cups being deeper than the corrugations form a space, a sort of by-pass, 9 behind the wooden insert 6 through which the dust may fall around any horizontal insert 6 and escape downward through the vertical corrugations 4 and this is a desideratum.

The edges of the end sheet may be flanged 20 on the side as is indicated by 10 Figs. 5 and 6 and the corrugations may terminate at 11, Fig. 5 or be carried around the corner and terminate at 12, Fig. 6.

The end is suitably fastened to the corner 25 post 13 by bolts 14 or by other suitable means or other arrangement of bolts as desired.

The inside sheathing for the side of the car is indicated by 15 and a corner strip is 30 indicated by 16.

The top and bottom edges of the end may be left flat and bolted to the end sills and end plate. 17 indicates the end plate and 18 the roof and 19 the top of the end sheet, 35 Fig. 3.

In Fig. 4 the top of the end is flanged over as is indicated by 20.

The splice between the sheets that compose the end when the same is made of more 40 than one piece is made to occur across the corrugations and not the cups for convenience and the corrugations are so made that they extend across the splice as is indicated by 2, Fig. 2 and the splice is riveted or 45 bolted or otherwise suitably fastened, 21 indicating rivets for this purpose. This arrangement of the splice carries the stiffness across the splice and secures with spliced sheets the substantial effect of a continuous 50 sheet.

By my construction I get an end stiff in every direction. Should it be desired I may make my end with a bulge outward in the middle portion and still retain the stiffening corrugations and cups.

I may cause the flanged edges of my end to act as corner posts and end plate or either separately as desired. The flange 20 may be so made as to furnish all the strength required for it to perform the function of the end plate without reinforcement.

A sheet embossed with ribs and cups as I have indicated is a very stiff sheet even if the cups are not appreciably deeper than 65 the ribs and a good end can be made that

way, but not as good an end as when the cups are deeper than the ribs.

What I claim is:

1. The combination with an internally flat sheet metal car end provided with a set of 70 embossed ribs extending upwardly from points near the floor line, with a second set of ribs of like character intersecting the ribs of the first set, and with materially deeper embossed cups at the points of intersection, 75 respectively, of strips secured in some of the ribs and extending across the deeper cups into which the ribs merge, and wood sheathing secured to said strips, covering the inner face of the metal and forming therewith 80 continuous open passages in all ribs not filled by the strips.

2. In a metal car end, the combination with a metal sheet having its constituent metal deflected to form external ribs or corrugations extending along vertical and horizontal intersecting lines and merging into integral deeper cups at the points of intersection, respectively, of wooden inlay strips 85 fixed in certain of the vertical corrugations 90 or ribs, and wood sheathing secured to the inlay strips.

3. The combination with a sheet metal car end provided with embossed ribs extending along intersecting lines, inlay strips fixed in 95 certain of said ribs, and sheathing secured to the inlay strips, the downwardly extending ribs being carried outward at the points of intersection to form by-passes around any inlay strips in the ribs met by said downwardly extending ribs.

4. The combination with a sheet metal car end having its lateral marginal portions bent to fit against the car's sides and its body provided with vertical embossed ribs, with 105 horizontal embossed ribs continued into said portions, and with materially deeper embossed cups at the points of intersections of the two sets of ribs, of wood strips fixed in certain ribs of one set, and internal sheathing 110 fixed to said strips.

5. In a car end, a heavy metal sheet constituting the main strain-resisting element of the end wall and consisting of a primarily plane sheet pressed outward along 115 many lines to form two intersecting sets of narrow integral stiffening ribs distributed with approximate uniformity over the car end.

6. In a car end, a heavy metal sheet constituting the main strain-resisting element of the end wall and consisting of a plane body pressed outward along a series of many parallel lines to form a set of narrow stiffening ribs extending approximately across 125 the car end and pressed outward along a series of other lines to form many similar ribs intersecting the ribs of the first set.

7. In a car end, a sheet of metal constituting the main strain-resisting element of 130

the end wall and consisting of a primarily plane sheet pressed outwardly along a plurality of angularly disposed lines to form a plurality of sets of relatively narrow intersecting stiffening ribs distributed with approximate uniformity over the surface of said sheet.

8. In a car end, a sheet of metal constituting the main strain-resisting element of the end wall and consisting of a primarily plane sheet pressed outwardly along a plurality of angularly disposed lines to form a plurality of joined sets of relatively narrow intersecting stiffening ribs distributed with approximate uniformity over the surface of said sheet.

9. In a car end, a heavy sheet constituting the main strain-resisting element of the end wall, and consisting of a plane body pressed outwardly along a series of sundry parallel lines to form a set of narrow stiffening ribs extending nearly across the car and pressed outwardly along a series of other lines to form sundry similar ribs in-

tersecting the ribs of the first set, in combination with marginal stiffening members adapted to coact with some of said stiffening ribs to transmit imposed stresses to car framing.

10. In a car end, a heavy metal sheet constituting the main strain-resisting element of the end wall and consisting of a primarily plane sheet pressed outwardly along sundry lines to form two sets of intersecting narrow integral stiffening ribs uniformly distributed over the car end, said sheet having angularly disposed edge flanges, and marginal stiffening members within said flanges adapted to coact with some of said stiffening ribs.

Signed in Chicago, in the State of Illinois and county of Cook this 23rd day of December, 1914.

WILLIAM ERASTUS WILLIAMS.
